GAS PRODUCER

Marc F. Charrier, Monticello, N. Y.

Application February 6, 1948, Serial No. 6,679

2 Claims. (Cl. 48—89)

1

This invention relates to the production of gas for illumination, power and other purposes, and it pertains more particularly to the generation of gas from straw, corn-cobs, weeds, husks, hulls, peat and other suitable waste materials. The gas is generated in a comparatively small apparatus, such as may be employed advantageously on farms and in other places where operation must be easy, and output small, compared with the mass production required for large cities.

With generators commonly so used, it has been found that the expenditure of fuel has been too great for the results obtained, and thus the product has been too costly in communities where fuel is scarce or its cost too high.

It is an object of the invention, to provide a generator so formed that the gas producing mass is quickly and uniformly brought throughout to the degree of temperature required for its destructive distillation, and evolution of all available gas therefrom, with the result that economy of fuel and time is attained.

A further object of this invention is to provide a gas producer with superimposed bank of fire flues, the lower bank, besides transmitting the flames, also acts as a support for the waste matter used in generating the gas.

Other novel features of the invention will appear from the following description, when read in connection with the accompanying drawing.

In the drawing:

Fig. 1 is a longitudinal section of the gas producer.

Fig. 2 is a section taken on line 2—2 of Fig. 1.

Fig. 3 is a modified form of producer.

The gas producer consists of an outer casing 10, which rests on the ground or a base 11, with a shell 12, resting on said base. The casing has a front wall 13, and a rear wall 14, and is covered with insulating material 15.

Within the casing 10, there is a retort 16, properly supported on an inverted arch 17, and on the bent in proportions of the outer shell 12. This retort 16, comprises a drum 18, with end walls 19, and 20, welded thereto. Through the retort 16, there extends a lower bank of flues 21, which are substantially at the center of the retort, and close together so as to retain the waste products. Through the upper portion of the retort 16, there extends a second bank of flues 22. An offtake 23 is connected with the retort from which the generated gases are abstracted by means of pipe 24.

The offtake 23, is provided with a safety valve, or weighted cover 25, hingedly affixed at 26.

2

Under the retort 16, there is provided an ordinary fire box 27, with a grate 28, and ash chamber 29.

The retort 16, is provided with two openings 30, and 31, which project into the front wall 13. These openings are used for inserting the waste material for generating the gas, as straw or other vegetable matter. The openings are kept closed by means of doors 32, and 33, operated in any desired manner.

The fire box 27, is provided with a door 34, and the ash chamber with a door 35.

Between the front wall 13, and the retort 16, there is provided a baffle 36, which extends 15 through the width of the retort 16.

A damper 37, set between the retort 16, and the rear wall 14, is adapted to control the flames so that they travel directly to the smokestack 38, or through the flues 21.

20 A pipe 39, at bottom of the retort 16, is provided and is used for removing sediment etc.

In the operation of the gas producer, the straw, peat or other vegetable matter is placed on the bottom of the retort 16, through the door 33.

25 Another portion of the same material is inserted through the door 32, and placed on the smoke flues 21, which act as a grate. The fire in the fire box 27, heats and decomposes the matter in the bottom of the retort, and the flames passing 30 through the flues 21, heats and decomposes the matter placed thereon.

The gases generated in the retort on rising upwardly are superheated by the flues 22, causing the separation of any substances carried by the 35 gases generated. The gases are then led off by means of a pipe 24, to the separator, purifier and expansion chamber and ready for use.

In Fig. 3, a modified gas producer is shown. Here the casing 40, has two boxes 41 and 42, in 40 which the waste matter is placed through doors 43, and 44. A fire box 45, and a fire box door 46 is provided. An ash door 47, through which the ashes are removed. Baffle plates 48, and 49, direct the flames in a tortuous path so as to 45 thoroughly heat the boxes. Gas offtake pipes 50, and 51, are connected to the boxes 41, and 42, and lead off to the separator, purifier and expansion chamber and ready for use.

As various changes may be made in the above 50 embodiment without departing from the spirit of the invention, it is to be understood that all matter herein is to be interpreted as illustrative, and not in a limiting sense.

What I claim is:

55 1. In a gas producer, a fire box, a retort above

said fire box, said retort being divided into two gas generating chambers, with separate means of access to each chamber, a plurality of combustion flues, said flues forming the division between the generating chambers, and arranged to function as a grate for the upper chamber.

2. In a gas producer, a fire box, a retort above said fire box, said retort being divided into two gas generating chambers, with separate means

of access to each chamber, a set of combustion flues, said flues forming the division between the generating chambers, and arranged to function as a grate for the upper chamber, and a second set of flues passing through said retort near the top thereof for superheating the generated gases.
